UNITED STATES PATENT OFFICE.

BERNARD REIN, OF URBANA, ASSIGNOR TO JOHN FOOS, OF SPRINGFIELD, OHIO.

VAPORIZER AND BURNER FOR GASOLINE AND OIL STOVES.

SPECIFICATION forming part of Letters Patent No. 336,745, dated February 23, 1886.

Application filed October 18, 1884. Serial No. 145,865. (No model.)

To all whom it may concern:

Be it known that I, BERNARD REIN, a citizen of the United States, residing at Urbana, in the county of Champaign and State of Ohio, have invented certain new and useful Improvements in Vaporizers and Burners for Gasoline and Oil Stoves, of which the following is a specification, reference being had to the accompanying drawings.

10 My invention relates to vaporizers for gasoline and coal oil stoves.

The primary object of the invention is to provide a vaporizer for hydrocarbons that will quickly and completely volatilize light and 15 heavy oils. Again, a desired object is to provide a vaporizer which can be opened and cleaned.

The several objects desired are attained by the construction of a vaporizer as shown in 20 the accompanying drawings, and which will be hereinafter described in the specification.

In the drawings, Figure 1 is a side elevation of my improved vaporizer and the pipes leading from the supply and to the oil-cup; Fig. 25 2, a plan view of same, and Figs. 3 and 4 sections of same.

Referring more particularly to the drawings, the vaporizer A is shown with pipe-connections C D, of the usual form and construction. The 30 vaporizer A, of any desired form, is provided with interior corrugations, a. These channels or corrugations are preferably in the form of a volute. A cover, B, makes the vaporizer air-tight. I may, however, make the vaporizer in the form of a coil, as shown in Fig. 2.

35 In every instance the vaporizer is made of copper or an alloy containing a preponderance of copper.

It is well known that the vaporizers in coal- 40 oil and gasoline stoves ultimately become foul

by reason of a deposition of carbonaceous matter on the sides of the vaporizer. This checks the ready heating of the vaporizer, and causes, to a certain extent, the noxious odors given off by such stoves. In my device this is remedied by the removable cap or cover B, which permits the interior of the oil-chamber to be reached and any sediment or deposit removed. The coiled or volute surface of the interior has the function of causing the oil and vapors to travel over a greater surface, so that in its passage the vaporization will be complete and waste avoided. I find by this construction that the heaviest hydrocarbons can be utilized for consumption in oil or gasoline stoves quite as readily and with as good results as the lighter refined and more expensive oils or fluids.

The form of the vaporizer may be round, rectangular, oval, or it may be of copper pipe, 60 as desired. The channels a may be deep or shallow, as may be deemed preferable, and the cap B be secured to the chamber A in any suitable air-tight way.

Having thus described my invention, what I 65 claim as new, and desire to secure by Letters Patent, is—

A vaporizer for gasoline or oil stoves consisting of the chamber A, having a continuous interior open volute channel, a, in combination with the removable cover and an oil supply and delivery pipe, substantially as and for the purpose set forth.

In testimony whereof I affix my signature in presence of two witnesses.

BERNARD REIN.
